KNIFE ADJUSTING MEANS FOR POWER SHEARS

Kirwan Y. Messick, Arlington, Va.

Application September 29, 1948, Serial No. 51,710

7 Claims. (Cl. 164—47)

1

The object of the present invention is to provide improved means for adjusting the upper knife blade of a power shear for the purpose of providing proper clearance between the upper and lower knife blades of such a shear. The proper adjustment of the clearance of these blades is a matter of great importance. If the adjustment is too close, especially where the stock being worked upon is relatively heavy, serious damage to the knives and to expensive machines may result. If, upon the other hand, the clearance is too great, especially where relatively thin stock is being worked upon, the resultant cut will not be a clean one. The power shears already on the market are provided with means for adjusting the clearance between the knives. However the adjusting means usually provided require so much work and so much time for the adjustment, that impatient workmen have fallen into the habit of setting the blades at an intermediate point and letting them stay there irrespective of the thickness of the material being cut.

This has resulted, as before stated, either in damage to the knives or in the stock being partially mashed instead of being cleanly cut.

The means by which I overcome the foregoing difficulties will be best understood by reference to the accompanying drawings wherein:

Fig. 1 is a partial plan of a power shear provided with the devices of my invention;

Fig. 2 is a perspective view of a portion of one end of the machine with the operating mechanism for the upper knife plate, omitted;

Fig. 3 is a transverse vertical sectional view upon line 3—3 of Fig. 1;

Fig. 4 is a transverse vertical sectional view upon line 4—4 of Fig. 2, through one of the end members of the frame;

Fig. 5 is a perspective view of an operating cam hereinafter described; and

Fig. 6 is an end view of said cam and its operating handle showing the latter associated with an indicating scale.

Like numerals designate corresponding parts throughout the several figures of the drawings.

In cutting shapes of relatively heavy steel the pressures which have to be exerted by the knives run up into thousands of pounds. Therefore these machines must be of very rugged construction and of such a nature as to resist these high pressures. The machine illustrated in Figs. 1 and 2 comprises a pair of very heavy steel end plates 5 which are tied together by a like heavy steel plate 6 at the rear of the machine and by other conventional uniting structure, not shown.

A heavy steel work table 7 comprising the horizontal portion 7a and the vertical portion 7b has its opposite ends resting upon forward extensions 8 of the end plates 5. The end plates are cut out as indicated at 9 so that relatively wide stock may be placed upon the work table and split lengthwise by being passed into a position between the lower knife blade 10 and the upper knife blade 11. Extensions 12 upon the work table extend outwardly and rest upon the edges 13 of the end plates 5. Adjusting bolts 14 bear between the extensions 12 and the upstanding portions 8 of the end plate and act, when turned in one direction to thrust the work table inwardly. Like adjusting bolts 15 act between the upstanding portions 8 and a depending apron 16 upon the work table to adjust the table in the opposite direction. This movement of the table moves the lower knife blade inwardly or outwardly as the case may be, said lower knife blade being seated in a recess 10a of the table and being backed up and stiffened by the wide vertical extension 7b of the work table. A depending apron 17 upon the work table is engaged by binding bolts 18 which operate in slots 19 of the end plates and which bolts serve to bind the work table firmly in place after it has been adjusted. The structure so far described is a well-known and conventional one and is one of the means heretofore employed for effecting an adjustment of the knives. I may retain this structure for the purpose of getting a coarse adjustment. However the necessity of loosening a number of bolts such as those indicated at 18 and then adjusting the table and thereafter tightening said bolts makes this operation somewhat time consuming and troublesome. The present invention, as stated, resides especially in the means which I have employed for securing a quick adjustment of the upper knife blade 11 and many conventional features have been omitted since the present invention relates only to the adjustment of said upper knife blade. As will be seen by reference to Fig. 2 this knife blade is seated in a cut out portion 20 of a heavy vertical reciprocating knife plate 21. Any of the conventional means may be employed for vertically reciprocating this plate. One such means is illustrated in Fig. 3, it being understood that these means are duplicated at each end of the press. Here the knife carrying plate 21 is connected by link 22 with a pivot 23 at the end of a crank arm 24. This crank arm is pivotally mounted at 25 upon the adjacent end plate 5 and it may have the necessary motion imparted thereto by the vertical re-

ciprocation of a rod 26. The rod 26 may be the piston rod of a hydraulic cylinder 27 or it may be any kind of a link connection between arm 24 and suitable mechanical actuating means.

The knife plate 21 and the knife blade 11 carried by said plate are mounted for vertical reciprocation in a carrier head. Vertical ways of said head receive the knife plate, said ways being constituted at the front side of the plate 21 by gibbs 28 and at the rear side of the plate 21 by the flat front faces 29 of the carrier head in which the knife plate is mounted. This carrier head comprises a front plate 30 and rearwardly extending forked members 31 and 32 said front plate and forked members moving together as a unit. The forked members comprise the spaced plates 33, 33a, 34, 34a. These last named plates, which make up the forked members, are pivoted at their lower ends to the end plates 5 upon pivots 35 and the adjustment of the upper knife blade is effected by tilting the upper portion of the carrier head fore and aft upon these pivots 35 and across the plane of movement of knife plate 21. The mechanism by which this fore and aft adjustment is secured is best illustrated in Figs. 3, 4 and 5. Here it will be seen that those portions of the heavy end plates 5 which lie between the plates 33, 33a and 34, 34a are cut out to provide openings of rectangular formation indicated at 37 and which openings extend all the way through the ends 5. Rectangular blocks 38 are seated in said openings and are capable of vertical movement therein but are incapable of lateral movement therein. These blocks have circular openings 39 formed therethrough which receive the large circular portions 40 of the operating cams hereinafter described and shown in Fig. 5. Projecting from the opposite ends of the portions 40 are smaller portions 41 which are offset or eccentrically disposed with respect to the portions 40 and these smaller portions 41 pass through and engage and turn in openings 41' formed in the plates 33, 33a or 34, 34a. It is apparent that if a turning movement be imparted to the cam of Fig. 5 the upper portion of the carrier head along with the knife carrying bar 21 will be tilted forwardly or backwardly according to the direction of such rotation. The reason that such fore and aft adjustment of the upper portion of the carrier takes place is that since the block 38 cannot move back and forth it follows that the smaller portions 41 will themselves move fore and aft and that the whole upper portion of the carrier head will follow such movement and swing backwardly or forwardly as the case may be about the centers provided by the pivots 35. Any suitable operating handle may be provided for imparting the desired turning movement to the cam of Fig. 5. One simple structure is illustrated in said figure and consists of a rod 44 which passes through one of the small end portions of the cam. The end of this rod is bent to substantially L-shaped as indicated at 45 and after the rod has been utilized as a crank to impart the desired turning movement to the cam this L-shaped end may be swung around to cause its point 46 to engage in any one of the openings 47 formed in the adjacent plate 33 or 34a as the case may be. This will lock the cam in the position to which it has been adjusted and the degree of such adjustment may be ascertained by noting the position of the pointed end 48 of rod 44 with respect to a scale 49 formed upon the plate 33 or 34a as the case may be.

Thus it will be seen that the cams and their associated parts (which will normally have to be moved very little) not only serve to lock the carrier head in the position to which it is moved by the cams but that these cams are the actual actuating means of the carrier head and that through them a very fine adjustment of the movable knives, may be had. Adjustment of the gibbs 28 may be effected by adjusting bolts 50 in the usual way. It will be observed that since the carrier head moves about a pivot point 35 that is relatively close to the knife blade that is being adjusted, and that since the adjusting cam is at a point far removed therefrom and almost in a line with said pivot, the reverse pressure upon the knife in cutting can have little effect tending to move the cam, after it has once been adjusted. It will further be observed that by locating the adjusting means at the point shown, they are brought to the upper forward corners of the press where they can be easily reached by a workman. Thus adjustment may be effected almost instantly and with such a little loss of time and with such little effort that there will be no temptation upon the part of the workman to neglect the adjustment to that point where the most effective work will be done. In presses of the character to which this invention relates the knife carrying plate is usually made quite large and heavy so that upon the working stroke the force of gravity will aid in effecting the cut. The manner in which I mount the knife adjusting mechanism lends itself to the easy adjustment of this large and heavy member, effects a very fine adjustment by multiplying the movement at the pivot point 35, at the adjusting member 44 and yet prevents the kick back of the knife from acting too forcibly upon the adjusting cam.

Many ways will readily suggest themselves to those skilled in the art for modifying the structure herein shown while retaining the principles embodied herein. Therefore it is to be understood that the invention is not limited to the precise arrangement shown, but that it includes within its purview whatever changes fairly come within the scope of the appended claims.

Having described my invention what I claim is:

1. In a machine for shearing metal sheets and the like, a pair of end frame means and a bed extending therebetween and fixed rigidly thereto, said bed including a work table having a stationary lower shear knife fixed to the rear edge thereof, each of said end frame means comprising a wall portion extending above and rearwardly of said work table, said wall portions being spaced in the direction of shearing, a reciprocable crosshead including an upper shear knife, slideway means for guiding the opposite end portions of said crosshead in a generally vertical path of movement to effect shearing strokes, means pivotally connecting said slideway means to the forward ends of said wall portions above said stationary shear knife, and means on said end frame means for selectively adjusting the slideway means upon its pivoting means and transversely of the plane of the knives, for adjusting the clearance between the knives.
2. In a machine for shearing metal sheets, a pair of end frame members and a bed extending therebetween and fixed rigidly thereto, said bed including a work table, a stationary lower shear knife extending along the rear edge of the work table, a reciprocable cross head including an upper

shear knife which coacts with said lower shear knife in the cutting action, a carrier head within which said cross head is mounted to slide in substantially vertical reciprocation, means for pivoting the carrier head upon said end frame members, said pivoting means mounting the carrier head to permit its upper portion to tilt transversely of the work table and knives, and adjusting means acting between said end frame members and the carrier head for imparting such transverse tilting movement to the carrier head and the cross head mounted therein, the pivoting means of the carrier head being located adjacent the lower end of said head and below the adjusting means but above the level of the lower shear knife.

3. In a machine for shearing metal sheets or the like the combination with a frame comprising a pair of end frame members and a work table extending between and affixed to said end frame members, a fixed lower shear knife extending along the rear edge of the work table, a carrier head extending throughout the length of the frame and provided at its ends with vertical slideways, a crosshead mounted for substantially vertical reciprocation in said slideways, an upper shear knife secured along the lower edge of the crosshead for coaction with the fixed shear knife, pivoting means located above the level of the lower shear knife by which the lower, rear corners of the carrier head are pivotally mounted upon the end frame members, said pivoting means being such as to permit the upper portion of the carrier head to swing transversely of the plane of movement of the crosshead, and graduated adjusting and holding means acting between the end frame members and the carrier head, to impart such transverse movement to the carrier head.

4. A structure as recited in claim 3 wherein the adjusting means comprise rotative members mounted to turn in the end frame members and eccentrically disposed portions carried by the rotative members which engage the carrier head to effect an adjustment thereof.

5. A structure as recited in claim 3 wherein

the carrier head comprises a front plate and a pair of inwardly directed plates at each end of said front plate between which end plates of the pairs the end frame members are received, the pivoting means of the crosshead passing through said end frame members and said inwardly directed plates at the lower ends of the latter plates.

10 5. A structure as recited in claim 3 wherein the adjusting means for the carrier head comprise blocks mounted for limited vertical sliding movement in the end plates, cams having a part of one diameter mounted to turn in said blocks and eccentrically disposed projections which engage the upper portion of the carrier head to transversely adjust the latter upon its pivoting means.

20 6. A structure as recited in claim 3 wherein the adjusting means for the carrier head comprise blocks mounted for limited vertical sliding movement in the end plates, cams having a part of one diameter mounted to turn in said blocks and eccentrically disposed projections which engage the upper portion of the carrier head to transversely adjust the latter upon its pivoting means, graduated, manually operable means for turning said cams and locking means between said operating means and the carrier head for holding the cams and carrier head in their adjusted positions.
